UNITED STATES PATENT OFFICE.

CANDIDO TORRES, OF ARDMORE, SOUTH DAKOTA.

COMBINATION LIFE BUOY AND SWIMMING DEVICE.

Application filed August 20, 1925. Serial No. 51,339.

To all whom it may concern:

Be it known that I, CANDIDO TORRES, a citizen of Mexico, residing at Ardmore, in the county of Fall River and State of South Dakota, have invented certain new and useful Improvements in Combination Life Buoy and Swimming Devices, of which the following is a specification.

This invention relates to improvements in swimming apparatus, and it is the principal object of the invention to provide a combination life-buoy and bathing or swimming device which may also conveniently be used for teaching swimming etc.

Another object of the invention is the provision of a device of this character which is extremely simple and which can be readily attached to a person.

A further object of the invention is the provision of an apparatus of this kind allowing the free use of the legs and adapted to keep a person above water.

A still further object of the invention is the provision of an apparatus of this type having a pair of side wings, and operating means therefor.

These and other objects and advantages of the invention will become more fully known as the description thereof proceeds, and will then be more specifically defined in the appended claims.

In the accompanying drawing, forming a material part of this disclosure:

Fig. 1 is a top plan view of a combination life-buoy and swimming device constructed according to the present invention.

Fig. 2 is a side elevation thereof, partly in section on line 2—2 of Figure 1.

Fig. 3 is a sectional detail view of a clamp part.

The device comprises two floats 10 and 11 supported on a platform 12, having a front board 13 having a centrally located eye 14 to which are pivotally secured, intermediate their ends, by means of a pin 15, two arms 16 and 17, having at their front ends glove-like, hand receiving members 18 and 19, supported on arms 20', while the rear ends of the arms 16 and 17, are segmentally formed and provided with teeth 20 and 21, adapted to engage or mesh with teeth of gears 22 and 23 on stub shafts 24, to which are attached bars 25, on lateral wings 26, the opposite ends of which have

springs 27 attached thereto, the other ends of which are attached to angular brackets 28 engaging at their apexes over the neck-shaped ends 29, of floats 10 and 11, and adapted to be pressed together at their lower ends, one of which carries a spacer 30.

A belt 31 has forked or spaced ends equipped with buckles 32, adapted to be engaged by perforated straps 33, to attach the device to a person.

The operation of my device will be entirely clear from the above description, and need not further be explained. A person using the apparatus, will assume the position shown in broken lines in Figure 2 and will be protected against submersion by the floats, while he may conveniently make the customary swimming motions with his hands and while his legs are unhampered.

It will be evident that many changes may be made in my apparatus, described and shown, as an example, without departure from the spirit and principle involved.

Having thus described my invention, what I claim as new, and desire to secure by Letters Patent, is:

1. A combination life-buoy and swimming apparatus comprising a pair of floats, a platform carrying said floats, a pair of movable arm guides pivotally secured to said platform, means on said guides for receiving the hands of a person, a pair of wings, means for transmitting the movements of said arm guides to said wings, and a means for securing said apparatus on a person.

2. In an apparatus of the class described, a pair of floats, a platform for carrying said floats, a front board, a pair of arms pivotally attached intermediate their ends to said platform, hand guides at one end of said arms, the opposite end segmentally shaped and provided with teeth, a pair of gears adapted to mesh with said teeth, a pair of wings to which the motion of said gears is transmitted, springs for controlling said wings, and a means for holding the parts in their relative positions.

3. An apparatus of the class described comprising a pair of floats, a platform carrying said floats, a pair of wings, means for operating said wings, springs for limiting the operation of said wings, and end clamps for holding said floats on said platform to

which said springs are attached, and a belt for securing the device to a person.

4. An apparatus for swimming purposes comprising two elongated floats, a frame carrying said floats, wings, means for imitating the arm motion of a swimmer, means for transmitting said motions to said wings,

springs on said wings and end clamps to which said springs are secured, each having two brackets, and means for clamping the ¹⁰ neck parts of said floats to said frame.

In testimony whereof I have affixed my signature.

CANDIDO TORRES.
